CLAIM

The ornamental design for a toilet safety frame, as shown and described.

DESCRIPTION

FIG. 1 is a top, front, left-side perspective view of a toilet safety frame showing my new design;

FIG. 2 is a bottom, rear, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a top, front, left-side perspective view of the toilet safety frame in an environment of use.

The broken lines shown in the drawings illustrate portions of the article, and environmental structure, and form no part of the claimed design.
